NECKTIE FOR AN OPEN-COLLAR SHIRT

H. Heath Webb, 216 Applewood Lane,
Virginia Beach, Va. 23452

Filed Oct. 16, 1973, Ser. No. 406,825

Term of patent 14 years

Int. Cl. D2—05

U.S. Cl. D2—354

FIG.1

FIG. 3

FIG. 1 is a front elevational view of a necktie for an open-collar shirt showing my new design;

FIG. 2 is a front elevational view of a modified form of a necktie for an open-collar shirt showing my new design wherein the bottom portion is slightly wider than it is in the FIG. 1 form; and

FIG. 3 is a right side elevational view of the FIG. 1 form.

I claim:

The ornamental design for a necktie for an open-collar shirt, as shown and described.
